CLAIM

The ornamental design for pants, as shown and described.

DESCRIPTION

FIG. 1 is a front, top, right perspective view of a first embodiment of pants, showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a front, top, right perspective view of a second embodiment of pants, showing the new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

The long dashed broken lines depict features of the pants that form no part of the claimed design. The short dashed broken lines define portions of the pants that form no part of the claimed design. The uneven broken lines define the bounds of the claimed design and form no part thereof.

1 Claim, 14 Drawing Sheets
